UNITED STATES PATENT OFFICE

96,846

DESIGN FOR A CLOTHESPIN

William K. McBrier, Miami, Fla., assignor of one-half to Flora S. Scott, Wilkinsburg, Pa.

Application April 19, 1935, Serial No. 56,473

Term of patent 14 years

To all whom it may concern:

Be it known that I, William K. McBrier, a citizen of the United States, residing at Miami, in the county of Dade and State of Florida, have invented a new, original, and ornamental Design for a Clothespin, of which the following is a specification, reference being had to the accompanying drawing, forming part thereof.

I claim:—

The ornamental design for a clothespin as shown.

W. K. McBRIER.
